[57] **CLAIM**

The ornamental design for a holder for vehicle fire extinguisher, flare and maps, as shown and described.

DESCRIPTION

FIG. 1 is a front perspective view of a holder for vehicle fire extinguisher, flare and maps, showing our new design.

FIG. 2 is a front elevational view thereof.

FIG. 3 is a top plan view thereof.

FIG. 4 is a bottom plan view thereof.

FIG. 5 is an elevational view thereof taken from the end, as seen from the right of FIG. 2.

FIG. 6 is an elevational view thereof taken from the end, as seen from the left of FIG. 2.

FIG. 7 is a rear elevational view.

FIG. 8 is a front perspective view of a modification of the vehicle fire extinguisher, flare, and map holder of FIG. 1, wherein a side wall is hinged instead of an end wall.

FIG. 9 is a front elevational view thereof.

FIG. 10 is a plan view thereof.

FIG. 11 is a bottom plan view thereof.

FIG. 12 is an elevational view thereof taken from the end, as seen from the right in FIG. 8.

FIG. 13 is an elevational view thereof taken from the end, as seen from the left in FIG. 8.
